UNITED STATES PATENT OFFICE.

CLARK S. COMSTOCK, OF BLOOMFIELD, NEW JERSEY, ASSIGNOR TO
PORTER BROTHERS & CO., OF NEW YORK, N. Y.

DESIGN FOR A BUCKLE.

SPECIFICATION forming part of Design No. 25,831, dated July 28, 1896.

Application filed June 4, 1896. Serial No. 594,328. Term of patent 7 years.

To all whom it may concern:

Be it known that I, CLARK S. COMSTOCK, a citizen of the United States, residing at Bloomfield, in the county of Essex, State of New Jersey, have invented and produced a new and original Design for Buckles, of which the following is a specification, reference being had to the accompanying drawing, which shows a face view thereof.

The leading feature of my design consists of a loop located at the extreme lower end of one part of the frame and from which the sides of said frame diverge, the latter being subsequently bent or turned inwardly toward each other and then upwardly, ending in a pair of tongues.

Referring to the drawing, A represents a

loop formed at the extreme lower end of the article, the upper sides of which come in close proximity to each other, as shown at *a a*, from which points the sides B of the buckle diverge, said sides at their upper ends being bent inwardly, as shown at *b b*, and upwardly into tongues, as shown at *c c*.

C is the upper loop or part of the buckle-frame bent or shaped into the form as shown.

What I claim as new, and desire to secure by Letters Patent, is—

The design for a buckle substantially as shown and described.

CLARK S. COMSTOCK.
